HEEL-SETTING MEANS

Walter A. Thum, St. Louis, Mo., assignor to
United Shoe Machinery Corporation, Paterson,
N. J., a corporation of New Jersey

Application September 18, 1934, Serial No. 744,561

43 Claims. (Cl. 12—125)

This invention relates generally to means for mounting wood heels upon shoes.

In mounting a heel on a shoe, a common practice is to glue the cup of the heel to the heel-seat, 5 and afterwards the flap of the sole is glued to the breast of the heel. The successful accomplishment of this stage in shoe-manufacture is dependent upon the proper location and retention of the heel on the shoe during the glue-setting 10 operation. Unless the heel is properly placed and fixed on the shoe while the adhesive is hardening, the security of the fastening of the heel to the shoe and the appearance of the finished shoe are impaired. I have found, however, that if the application and maintenance of the pressure to the work is automatic or under machine-power, and the gluing of the flap to the heel-breast is done while the shoe-assembly remains rigidly clamped, the speed of performance of this 15 operation is increased, while the accuracy of the work is practically assured, because the several parts are held securely in full view of the operator, the result being a greatly increased production, a saving in machine and labor costs and an improved product. In carrying out my invention, I prefer to employ a shoe-assembly-clamping means or heel-set, one embodiment of which I have described in Letters Patent of the United States No. 1,756,708, granted to me April 29, 1930, 20 and which will hereinafter be briefly described, but I have made certain improvements in the construction and operation of said heel-set. These improvements more particularly involve the application of setting pressure to the clamped 25 work by separate means, as a pedal actuated by the operator and mechanism functioning under the power of a machine in which the work with its heel-set or clamping members is supported between pressure-abutments; means, also operated under the power of the machine, for locking 30 the clamping members in pressure-applying relation; novel means for fixing one of the abutments in the position to which it is moved; an arrangement for suspending the heel-set upon the upper 35 abutment to facilitate the application of the work thereto; an unlocking organization for the clamping members; the combination with the heel-set of a flexible member arranged for contact with both the tread and rear of a heel and adapted 40 to bend and otherwise adjust itself as to position when clamping pressure is applied; and flap-pressing means mounted upon the heel-set and movable thereon to urge the flap into engagement with the breast of the heel.

Fig. 30 is a fragmentary transverse sectional 35 view of the shoe-assembly, illustrating the frontal face of the heel as seen after the flap-press has been removed, and showing appearance of the untrimmed flap after the same has been glued to the heel and the adhesive has hardened; and

40 Fig. 31 is a top plan view of Fig. 30.

It may be briefly stated that by the present embodiment of the invention provision is made for applying glue or other adhesive to a heel by passing the cup thereof over a power-actuated 45 glue-feeding device, and the heel assembled on the shoe. Then, by clamping means co-acting with my before-mentioned heel-set, the heel-and-shoe-assembly is rigidly supported during succeeding operations. While so supported, an 50 automatic power-actuated device is employed for pressing the heel on the shoe, and, in proper sequence, to operate a latching means conjointly with a pressing means to grip the shoe-assembly in the heel-set. A resilient heel-pressing device 55 carried by and co-acting with the heel-set in co-operation with a shoe-rest on the supporting frame fixes the heel on the shoe precisely in the position previously determined by the operative in assembling the heel and shoe. Then a power- 60 actuated rotary finishing device is manipulated by the operative for facing the breast of the heel preparatory to gluing the flap of the sole on the heel, and a flap-press, co-operating with the heel-set, yieldingly forces the flap against the breast.

65 The heel being thus clamped to the shoe and the flap clamped to the heel, the shoe-assembly as a unit is removed from the supporting frame. After the glue has hardened, the heel-set is removed with the aid of a mechanical device, and 70 a power trimmer is employed to trim the over-hanging part of the flap from the heel. This completes the operation. It is to be noted that the shoe-assembly, while held in the supporting frame, is disposed with the shoe-bottom in full

75 view of the operator, by reason of which the

speed of production is greatly increased and the quality of workmanship enhanced.

I will first generally describe the improved heel-set and the shoe-assembly. In Fig. 1, A designates the heel-set, which includes a U-shaped shackle member 1 of suitable dimensions for receiving the usual boot- or shoe-assembly B, as shown in Fig. 2. Preferably the member 1 is generally formed as I have heretofore set forth in the previously mentioned patent but having oppositely located shoulders 2 just above the bight of the member 1, for co-action with a flap-press, presently to be described. Disposed transversely of the member 1, is a cross member or latch-plate 3 provided at its opposite ends with enlargements 4, 4 bored to fit the legs of the member 1, whereby the plate 3 is disposed for shiftable movement relatively thereto. Upon their opposed inner faces, the enlargements 4, 4 are slotted across the top of the plate to permit engagement with the legs of the member 1 by the outer ends of aligned locking or latch members 5, 5, mounted to slide upon the outer face of the plate 3. Each latch member is formed with its outer end recessed to receive one of the legs of the member 1 (Fig. 20), and has its inner end inclined oppositely to a conical shoulder or cam-portion of a screw element 6. This screw has a hexa-conical head, for a purpose shortly appearing, and is threaded into the plate 3 for co-operation with the latch members 5, 5, so that when the element 6 is screwed into the plate, the latch members 5, 5 will be so oppositely moved outwardly as to engage the respective legs of the member 1 and thereby rigidly secure the members 1 and 3 together. Preferably, the spaced ends of the legs of the member 1 are slightly enlarged to prevent separation therefrom of the plate 3 upon disengagement of the latch members 5, 5.

The shoe-assembly B comprises a last 7 insertable in a shoe 8, upon which a heel 9 is to be secured by an adhesive. The cone of the last may be provided with the usual pin-hole 10. Disposed on the sole of the shoe 8 for engagement by the breast-edge of the heel is a shoulder 11 for heel-lining purposes, while the heel-cup contacts with the heel-seat on the shoe. This invention is particularly adapted for gluing on shoes heels of the spike or Louis type, and the practical requirement of heel-setting which it meets in a simple and highly effective manner is that during the hardening of the adhesive the heel is firmly pressed uniformly on the shoe. I have accomplished this object by disposing the heel-set A on the shoe-assembly B, with the aid of a preferably V-shaped slot 11^a provided transversely across the end of the cone of the last 7, (Fig. 18), for co-action with the bight of the member 1, so that the plane of the member 1, or the line of action of the heel-set, will pass through the forward half of the heel-seat on the shoe (Fig. 3), the precise location depending on the form of the heel and shoe. When so disposed, the heel-set will positively fix the heel as placed and it is a practical impossibility for the heel to "kick-over" or become loosened. While the shoe-assembly is supported in the frame during the pressing and latching operations, presently to be described, after the set-and-shoe-assembly is removed from the machine, the heel and the shoe are held together by the heel-set, no screws or other interconnecting fastening means being employed save the adhesive.

For setting spike or other high heels, I provide

a resilient bridging member or heel-engaging fixture C, shiftably supported from the heel-set A and interposed between the heel and the plate 3 of the heel-set. The member C is adapted for 5 self-adjusting contact with the heel 9, bending as it spans the space between the rear face and the tread of the heel 9 across the plane of the member 1 or the line of pressure-action of the heel-set A. It comprises a preferably flexible 10 body member or bridge-piece 12 whose rearward heel-face-engaging arm 13 carries a felt pad 13', or other yieldable covering and is curved to the approximate shape of the surface with which it is to contact. The forward arm 14 of the bridge 15 member has a lip 15 for engagement with the tread of the heel 9. Formed on the inner side of the plate 3 for sliding contact with the bridge-piece 12, to shiftably locate the latter in desired 20 relation with the heel 9, is an arcuate seat 16, the bridge-piece being loosely held to the seat by a screw or fastening element 17, preferably threaded into the screw 6 and movable in a slot in the member 12 as the fixture C swings on the plate 3 of the heel-set (Fig. 1a).

Having thus outlined the construction of my improved heel-set A and its heel-abutment C, a particular embodiment of a supporting frame or machine for use in connection with said heel-set will be described. Generally, the machine includes 25 a shoe-rest D, co-operating with a foot-operated clamping head E and with power-pressure mechanism F. The machine also preferably includes a glue-applying mechanism G and a power-operated finishing mechanism H having a cutter or 30 file (Fig. 17) all mounted on a single frame. This frame includes a floor-plate 18 and standards 35 19 rigidly supporting a bed-plate 20. Rising above the bed-plate 20 is the shoe-rest D, preferably guided in a block 21 extending through 40 and secured to the bed-plate 20. The guide-block 21 forms a part of the pressure mechanism F and is provided with a passage 22 (Fig. 15) to receive the bight of the U-shaped member 1. The heel-set A is so carried in the machine as 45 to be vertically presented in shoe-assembly-receptive position. For the convenience of the operator in mounting the shoe-assembly B in the frame, within and properly aligned with the heel-set, I provide, rearwardly of the passage 50 22 and on the shoe-rest D, a pair of laterally spaced upstanding guide-fingers 23, 23, for loosely receiving the cone of the last 7, and also an upstanding pin 24 between fingers 23 and inclined for co-action with last-hole 10. Between 55 the guide fingers 23, 23, the shoe-rest D is formed with a last-engaging curved face 25, in order that the last-and-shoe-assembly B may freely rock, with an amplitude limited by the engagement of the pin 24 with the walls of the hole 10 60 responsively to the pressing action of the head E (Fig. 15).

Fixed to the bed-plate 20 is a vertical, inverted L-shaped clamping frame 26, in the horizontal arm of which is slidably mounted the clamping head E adapted for adjustable movement towards 65 or away from the shoe-rest D to accommodate different sizes of shoe-assemblies. Vertical reciprocation of the head may be accomplished by a shifting mechanism which includes a pair 70 of racks 27 and co-acting pinions 27' connected, preferably through a yielding member or spring 28, to a foot-lever or pedal 29, the latter being provided with a releasable latching device 30. Downward movement of the pedal 29 will result 75 in yielding downward travel of the head E into

engagement with the shoe-assembly B upon the rest D, the spring 28 thereafter yielding to permit the completion of the movement of the pedal 29 to latched position, as indicated in Fig. 3. It will thus be seen that the operator has only to 5 depress the pedal to latched position to automatically adjust the head to any shoe-assembly. Said head may be retracted by a spring 28a on release of the pedal from the device 30. Depending from the head E, for alinement with, and reception of, the legs of the member 1 of the heel-set, are a pair of preferably tubular plate-engaging members 31, 31 (Fig. 5). Rotatable between the members 31, 31, is a socket member 32 adapted to engage and rotate the hexa-conical head of the 15 wedge member 6 of the heel-set A. The head E is thus advanced from the frame 26 for supporting the heel-set in position for operative co-action with the pressing mechanism F. To afford this support, the legs of the shackle member 1 are received by the tubular portions 31, 31 of the head E, with the ends of the bight of the shackle in engagement with the guides 23, 23, and in vertical alinement with the passage 22 of the shoe-rest, the plate 3 being detachably supported from the head by a means to be described. 20 25

The dimensions of the heel-set A are so chosen as to accommodate the largest size of shoe-assembly B to be operated upon, and so that at its maximum upward adjustment, the plate 3 will 30 be clear of the shoe-assembly as this is inserted into the heel-set for support by the shoe-rest D. As the plate 3 at this time is unlatched, and hence unless restrained may freely slide on the member 1, I provide a pair of plate-engaging fingers 33, 33 (Fig. 16), slotted to receive the legs of said member. The fingers are mounted on the head E, being supported on a shaft 33a rotatable in a yoke joining transversely opposed C-shaped extensions 34, 34 depending from the members 31, 31, 35 into which extensions the plate-enlargements 4, 4 respectively enter to rest on the fingers 33, 33 (Fig. 5). The fingers are normally urged upwardly by a spring to bear upon the plate-enlargements but, by a handle 34a secured to the shaft 45 33a, said fingers may be swung downwardly and to one side for the reception of the heel-set A. Thereafter, the fingers 33 are returned by their spring to plate-supporting position. The plate 3 is thus suspended from the head E with the bight 50 of the member 1 separated from it to the maximum extent, thus giving ample clearance to allow the ready positioning of the shoe-assembly B between the clamp members. The head E is actuated through the foot-pedal 29 to lower the 55 plate 3 and clamp the shoe-assembly B upon the shoe-rest D, as best seen in Fig. 3.

The socket member 32 is suspended by a cage 32' from a clutch member 36 provided with a corrugated end-face adapted to co-act with a complementary portion of the socket member during the latching operation. Rotation is thereby so transmitted from a driving member that the clutch will yield to resistance of the socket member 32 as the screw 6 is driven home. In 65 such yielding movement the clutch member 36 works against an expansible member or spring 35 between the clutch member and the head E. Journaled in the head for axial and rotatory movement is a vertical clutch-shaft 37 having its lower end between the plate-engaging members 31, 31 in axial alinement with the clutch member 36. This shaft has an axially yieldable driving connection 38 with the clutch 36. As will shortly appear, the shaft 37 is driven from the pressure 70 75

mechanism F. In clamping the heel-set on shoe-assemblies of different sizes, it is convenient to mount the shaft 37 for reciprocation in the head E, to accommodate the clutch 36 to the socket member 32 as the latter finds its seat on the screw member 6. The head is fixed in its adjusted position by a locking device, including preferably a double-ended handled clamping bolt 39 (Fig. 4), co-operating with a pair of members 40 pivotally supported from the frame 26 for oppositely pressing against the head a pair of friction members or blocks 41, 41, slideable through opposing walls of the frame. So locked in adjusted position in the frame 26, the head becomes temporarily a fixed abutment co-operating with the mechanism F.

As best seen in Figs. 17 and 18, a pressure-slide or lifting member 42 is reciprocable in the channel 22 of the shoe-rest D and has at its top a V-slot 42a (Fig. 18) adapted to co-act with the bight of the member 1. At its lower extremity the member receives contact of an arcuate seat on one end of a lever 43 fulcrumed on a bracket depending from the bed-plate 20. The lever is acted upon by a spring 43a (Fig. 6), which urges a roll 44, carried by its other end against a cam 45, this causing the alternate advance and retraction of the member 42 in the channel 22. The cam 45, which includes a rising portion a, a rest portion b of approximately 190°, and a falling portion c, is fixed on a main shaft 46 journaled in bearings depending from the bed-plate 20; see Fig. 2. Mounted on the shaft 46 is a single-rotation clutch mechanism generally indicated at 47, receiving power from a gear 48 turning about the shaft 46. The clutch becomes effective on actuation of a clutch-lever 49 through a clutch-pedal 50, best seen in Fig. 2. The clutch, details of which appear in Figs. 8, 9, and 10, is so well known that no further description is necessary. The gear 48 may be connected by a train of gears through a counter-shaft 52 (Fig. 6) with an electric motor 53 or other source of power supported upon the bed-plate 20. By this means, the main shaft 46 may, at the will of the operator, be caused to turn once, so the pressure member 42 will make one reciprocation. A brake device J (Fig. 7), including a friction band 20a adjustably mounted on the under side of the bed-plate 20 for co-operation with a disk 46 keyed to the shaft 46, has the effect of promptly bringing the shaft 46 to rest on termination of the operating movement of the clutch 47. Coincidentally with the movement of the slide 42, the shaft 37, before described as rotating in the head E, is actuated by a pair of bevel-gears 54, 55, one of which, as 54, is splined to the shaft 37 to permit the axial movement of the latter. From the bevel gears 54, 55, the operating connections are through shafts 56, 57 (Fig. 2) and 58 (Fig. 6) and pairs of bevel gears 60, 61 and 62, to a jack-shaft 63 intermittently rotated by mechanism which may be of the Geneva-stop type, or some such like mechanism. However, in the present instance I employ a discontinuous gear 64 (Fig. 12) mounted on the main shaft 46 for co-operation with a pinion 65 provided with a stop 66 having a depression for co-action with a land 67 on the gear 64, the manner of engagement being such that the depression will receive the land as the pinion is disengaged from the toothed portion of the gear. This construction transmits rotation to the shaft 37 in synchronism with the reciprocation of the pressure-slide 42, the shaft 37 being rotated during a portion of the rotation of the shaft 46, while the

land 67 is within the stop-depression during the other portion of the rotation of the shaft. I prefer that the shaft 37 be rotated during that portion of the cycle at which the slide 42 is at its most elevated position, while the roll 44 is riding on the rest-portion b of the cam 45. Preferably, the shaft 37 is locked against rotation before the rest portion of the cam leaves the roll.

The main shaft 46 may be extended forwardly from under the bed-plate 20 (Fig. 2) for connection with the glue-applying mechanism G, supported upon the machine-frame in a location convenient to the operator. This applying mechanism is illustrated in detail in Figs. 21 and 22. It preferably includes a glue-well or receptacle 68 having rotatable therein a feed-roll 69 connected at one end by worm-gearing 70 with the main shaft 46, and at its other end by spur-gearing 71 with the shaft of a brush 72 rotatable upon the receptacle 68. The brush 72 is preferably formed of circumferentially spaced longitudinal rows of bristles or fibers 73. The central portion of the ends of the fibers of each row is raised or bulged at 74 outwardly from the end portions, being approximately complementary to the hollow of the cup of the heel 9. The opposite ends of the portion 74 will come within the width of the narrowest heel to be operated upon by the machine, while its projection outside the adjacent end portions is greater than the depth of the largest heel-cup. The cross-sectional area of the portion 74, considered radially, is approximately equivalent to the corresponding area of the largest cup to be coated. The brush 72 is so partially rotated for each turn of the shaft 46 that successive rows of fibers 73 are presented above a cover-plate 75 upon the receptacle 68. The longitudinal peripheral contour of the roll 69 is generally complementary to the corresponding contour of the brush, and hence on such partial revolution a film of glue will be laid on the ends of the bristles of the successive rows thereof. To regulate the thickness of this film of glue, I provide a scraper-bar 76 pivotally mounted in the receptacle 68 for adjustment of its edge toward or from the periphery of the roll 69. This bar has an arm 77 (Fig. 22) engaged by a thumb-screw 78 for movement of the scraper-edge toward the roll 69, while a spring 79 retracts the bar on reverse movement of the thumb-screw.

Connected with the continuously revolving counter-shaft 52 by bevel-gearing 80 is a flexible driving cable 81 enclosed in a flexible cable-housing 82 (Fig. 6). A U-shaped frame 82 swings on the counter-shaft 52 for supporting the adjacent end of the housing 82, the other end of which is attached to one end of the power-operated finishing mechanism H (Fig. 25). This preferably includes a pair of axially aligned, spaced, tubular handles 83, 83, in which is journaled a shaft 84, having one end connected to the driving cable 81. Mounted on the shaft 84 between the inner ends of the handles 83 is a cylindrical finishing member 85, which may comprise a grinding medium, as an emery-wheel or the like, or the finishing may be done by means of a rotary cutter, as a file. The contour of the cutting periphery of the file may be of a shape conforming to the purpose in hand, a cylindrical portion 85a and a curved or bulbous portion 85b.

A flap-press K, adapted for co-operation with the heel-set A to firmly press the flap 8a of the sole of the shoe 8 against the breast 9a of the heel 9 during the drying of the adhesive employed, is illustrated in Figs. 15, 23, and 24. This

press includes an inverted U-shaped body or shackle member 86 formed to embrace the instep of the shoe 8. The end of each leg of the member 86 is formed with a hook 87 engaging one of the shoulders 2, 2, on the member 1 of the heel-set. The bight of the shackle 86 is preferably flattened and has medially threaded therethrough a thumb-screw 88, from the inner end of which is supported by a ball-and-socket or other universal joint 89 a pressure-plate 90. Secured to the plate is a resilient or yielding flap-engaging head 91, which I prefer to so form of sponge-rubber that it will fit upon the instep and against the heel, as shown in Fig. 15. Guide-pins 92, 92, 15 upstanding from the plate 90, freely slide through apertures provided in the bight of the member 86 in order that the head 91 may be approximately alined with its intended position on the shoe-assembly B when the flap-press K is hooked to the heel-set A.

In Figs. 19 and 20, I show one form of an unlatching device L for disengaging the heel-set A from the shoe-assembly B. This preferably comprises a pair of spaced, upstanding, plate-engaging, tubular members 93, 93, rigidly mounted on a base 94, for the reception of the legs of the U-shaped member 1 of the heel-set. Rotatable upon the base 94 between the members 93, and adapted for registration with the head of the 20 wedge member 6 of the heel-set, when the latter is disposed upon the device L with the plate member 3 resting on the upper ends of the members 93 and the legs of the member 1 received therein, is a ratchet-wrench-socket 95. The socket is 25 provided with a ratchet-handle 96, co-operating with a ratchet 97 on the socket member 95. When the shoe-assembly-heel-set unit A—B—C is mounted in upright position on the device L, the operator may, by simply rotating the socket 95 by 30 the handle, so loosen the wedge member 6 that the latches 5, 5, may easily be carried out of retaining engagement with the member 1, and the latter shifted upwardly with respect to the plate 3 to permit removal of the shoe.

In Figs. 26 and 27 is shown one form of a power-actuated trimmer or cutting mechanism M which I prefer to employ for removing the overhanging part of the flap 8^a after gluing said flap on the heel 9. On a frame 98, which may conveniently 35 be a bench, is journaled a guide wheel 99 for contact with the side of the heel at the breast-edges. The wheel has a portion 100, of reduced diameter, the upper surface of which furnishes means for lifting and feeding the margin of the flap to the cutter. A motor 101 carries upon an extension 101^a of its shaft a cutter or saw-like member 102, the cutting edge of which extends below the upper face of the wheel portion 100. I prefer to operate the cutter 102 tangentially to the wall 100, 40 so the shaft 101 lies diametrically of the wheel 99, and a guard 103 is provided, supported from the motor, for enclosing the cutter.

In Figs. 28 and 29 is shown another form of power-trimmer M', including a motor 101', shaft-extension 101^b and circular edge-cutter 102'. A platen 104 may be mounted on the frame 98 adjacent to the trimmer M, before described. The cutter 102' projects through a slot 105 in the platen. A guide 106 is adjustably mounted on the 45 platen for movement toward or away from the cutter 102'. I prefer to employ this trimmer M' for cutting off the end of the flap 8^a, the tread of the heel 9 engaging the guide 106 during the operation.

In practice I prefer to combine the shoe-rest D,

clamping-head E, pressure mechanism F, glue-applying mechanism G, and finishing mechanism H, in one machine, and to mount the unlatching means L and the power trimmers M and M' on a bench, which may or may not, as desired, form an extension of the bed-plate of the machine.

The first step in preparation for the operation of attaching a heel to a shoe consists preferably in mounting the unlatched heel-set A in the machine. For this purpose, the operator with one hand grasps the handle 34^a, and swings the fingers 33 to one side, while with his other hand he moves the plate 3 of the heel-set to the end of the U-shaped member 1, and inserts the enlargements 4, 4, of said plate into the C-shaped members 34, 15 34 of the head E, with the socket member 32 engaging the wedge member 6. The handle 34^a is then released, allowing fingers 33 to return to plate-supporting position, whereby the heel-set A is suspended from the head E and so held, 20 without further attention from the operator, as to leave ample clearance between the plate 3 and the shoe-rest D to receive the shoe-assembly B.

The next step is to apply the glue to the heel. 25 This operation has heretofore been one requiring considerable skill on the part of the operator, because the glue should be evenly applied over the cup of the heel and yet none allowed to escape around the edges of the cup to mar the appearance of the finished shoe. Furthermore, just enough glue for the purpose should be used, because if there is too much the surplus will be squeezed out from under the edges of the heel-cup, while if the amount of glue used is deficient, 30 the adhesion of the heel to the shoe is impaired. I overcome these difficulties by reason of the bulged portion 74 of the longitudinal peripheral contour of the rows of bristles, 73, on the brush 72 of the gluing mechanism G. By reference to 40 Fig. 21, it will be seen that the ends of the bristles along the cylindrical portions of the brush 72 are but a slight distance above the plate 75. Hence, the operator has only to grasp a heel in inverted position and move it across the plate 75 so that 45 the cup of the heel will receive the brush-portion 74, to quickly and accurately apply the glue to the surface of the cup. Because the brush at 74 is narrower than the smallest heel, there are no bristles projecting sufficiently above the plate 50 to cause any glue to adhere to the sides of the heel, while at the same time, since the height of the enlargement at 74 is greater than the depth of the largest heel-cup, the tendency of the bristles is to swing outwardly more or less radially 55 to the face of the cup, and deposit their carried film of glue evenly thereover. The thickness of this film is regulated by the scraper-bar 76, and a fresh row of bristles thus acted upon is presented above the plate 75 once during each cycle 60 of the operations. While the operator is applying the glue to the heel with one hand, with his other hand he holds a shoe-assembly B in an inverted position, with the bottom in view, and then places the glued heel on the heel-seat, holding 65 the breast-edge against the shoulder 11 of the shoe. Holding the shoe-and-heel-assembly with both hands, the operator slips it into the heel-set A, with the cone of the last between the guide-fingers 23 of the shoe-rest D and the hole 10 70 over the pin 24. This sufficiently alines the shoe-assembly in the machine and may be accomplished with great facility.

Still holding the heel in place on the shoe-assembly B, the operator depresses the pedal 29 75

to clamp said assembly between the head E and the shoe-rest D. He then manipulates the locking-bolt 39 to fix the assembly in the machine (Fig. 3). This accomplished, the operator depresses the clutch-pedal 50 for bringing the pressure mechanism F into operation. As the pressure-slide 42 rises on rotation of the cam 45, the walls of the V-groove 42a aliningly engage the bight of the member 1 to lift it through the plate 3, the latter being held by the head E acting as an abutment for the pressure mechanism F. As the member 1 rises, its bight enters into the groove 11a in the cone of the last (Fig. 18), while the latter fits between the shoulders 2, 2 (Fig. 17). The assembly B is thus positioned by the heel-set and yieldingly compressed between the bight of the member 1 and the heel-pressing fixture C, the latter freely swinging on the plate 3 until the bridge-piece 12 finds its seat on the heel. It will be seen from an inspection of Fig. 15, that, on lifting action of the slide 42, the fixture C distributes the pressure to the heel on both sides of the line of action of the heel-set A, thereby holding the heel uniformly on the shoe. This acts automatically to evenly seat the cup of the heel on the heel-seat of the shoe in the location determined by the operator, the line of resultant pressure passing through the forward half of the heel-seat of the shoe. When the roller 44 has received contact of the rest-portion b of the cam 45, the pressing action is completed, and the shaft 37 is rotated to latch the plate 3 in its shifted position on the legs of the member 1, thereby attaching the heel-set and its carried heel-contact member C on the shoe-assembly to securely hold the heel on the shoe. When thus pressed against the heel, the member C may rock and shift bodily upon the seat 16 and bend to adjust itself to the surfaces with which its ends contact. The several parts are now in the positions shown in Fig. 17. Upon termination of rotation of the pinion 65, the stop 66 co-operates with the locking land 67 on the gear 64, while the roller 44 contacts with the falling portion c of the cam 45, thus permitting the slide 42 to be retracted by the spring 43a.

The shoe-assembly B is now positioned in the machine between the head E and the rest D, the heel 9 being held under pressure on the shoe 8 between the fixture C and the shackle member 1 of the heel-set A. The breast 9a of the heel and the sole of the shoe are in full vision of the operator, who now takes in each hand a handle 83 of the mechanism H, and passes the finishing member 85 over the heel-breast to smooth it preparatory to gluing the flap 8a thereupon. This being accomplished, the operator applies adhesive to the heel-breast, and with his fingers stretches and smoothes the flap thereon. Then taking the flap-press K with the head 91 fully retracted, the operator hooks the shackle 86 under the shoulders 2, 2, of the heel-set, and turns the thumb-screw 88 to so force the head against the flap that uniform pressure is applied to said flap over the instep of the shoe and the breast of the heel (Fig. 15). The pedal 29 being released, the head E is raised by the spring 28a to its normal position and disengages the bight of the shackle member 1 from the rest D. This permits the heel-set-shoe-assembly A-C-K-B to be removed as a unit from the head.

Preferably, though not necessarily, the heel-set shoe-assembly is now laid aside until the adhesive has hardened. Then the heel-set A

and its heel-pressing means C and flap-press K may be removed from the shoe-assembly B. For this purpose, the operator mounts the assembly A-C-K-B in an inverted position in the unlatching mechanism L, with the legs of 5 the shackle 1 engaging the tubular members 93, and the head of the wedge member 6 within the socket member 95. A turn of the ratchet-handle 96 will loosen the plate 3 from the shackle, thus allowing the ready separation of the entire heel-set-assembly A-C-K from the shoe-assembly B. The untrimmed appearance of the breast-flap 8a is illustrated in Figs. 30 and 31. To finish the heel, the overhanging parts of the flap are trimmed flush with the sides of the heel-breast, 10 as suggested by the dotted lines 107 in Fig. 30, and the end of the flap is preferably trimmed short of the tread of the heel, or about where the lift and the heel proper are joined, as indicated by the dot-dash line 108 in Fig. 30. As 15 best seen in Fig. 26, one side of the heel 9 is brought against the periphery of the wheel 99, the latter having thus a rolling contact with the heel. The untrimmed side margin of the flap then lays on the portion 100 across the plane of 20 operation of the cutter 102. It is therefore lifted and fed to the cutter for severing the overhanging margin of the flap 8a along a line defined by the side of the heel, as the latter is moved by the operator. Having trimmed the sides of 25 30 the flap, the operator moves the shoe to the trimmer M' and places the tread of the heel against the guide 106 of said trimmer. He then slides the heel over the guide, to cause the cutter 102' to sever the end margin of the flap along 35 40 the line 107 to a width predetermined by the setting of the guide. This completes the operation of mounting and finishing the heel on the shoe.

It is to be understood that changes in the form, 40 construction, arrangement and method of use of the several parts, as set forth, may be made and substituted for those herein shown and described, without departing from the nature and principle of my invention.

Having described the invention, what I claim as new and desire to secure by Letters Patent of the United States is:

1. In a heel-setting machine, co-operating clamping members adapted for engagement with 50 a shoe-assembly and removable in clamping relation therewith from the machine, operating means for moving the clamping members into active relation to the shoe-assembly, and other operating means for applying pressure to the 55 clamping members.

2. In a heel-setting machine, co-operating clamping members adapted for engagement with a shoe-assembly and removable in clamping relation therewith from the machine, operating 60 means including a yieldable member for moving the clamping members into active relation to the shoe-assembly, and other operating means for applying pressure to the clamping members.

3. In a heel-setting machine, co-operating 65 clamping members adapted for engagement with a shoe-assembly and removable in clamping relation therewith from the machine, operating means for moving the clamping members into active relation to the shoe-assembly, and other 70 operating means including a lifting member for the clamping members.

4. In a heel-setting machine, a heel-clamp comprising a body member and an opposed clamping member movable upon the body mem- 75

- ber, opposite pressure members engaging the clamping members, and means individual to each pressure member for moving it from a normal work-receiving position toward the other pressure member.
5. In a heel-setting machine, driving mechanism by which the machine is operated, a heel-clamp comprising clamping members for a shoe-assembly, opposite pressure members engaging the clamping members, operator-actuated means for moving one pressure member, and means operable under the power of the driving mechanism for moving the other pressure member.
10. In a heel-setting machine, a heel-clamp comprising clamping members for a shoe-assembly, opposite pressure members engaging the clamping members, pedal mechanism by which one pressure member may be moved, and cam mechanism by which the other pressure member may be moved.
15. In a heel-setting machine, a heel-clamp comprising clamping members for a shoe-assembly, opposite pressure members engaging the clamping members, means individual to each pressure member for moving it toward the other pressure member, and means for locking one of the pressure members against movement.
20. In a heel-setting machine, a heel-clamp comprising a body member and an opposed clamping member movable upon the body member, opposite pressure members engaging the clamping members, means individual to each pressure member for moving it toward the other pressure member, and means for locking one of the pressure members against movement.
25. In a heel-setting machine, a heel-clamp comprising a body member and an opposed clamping member movable upon the body member, opposite pressure members engaging the clamping members, operator-actuated means for moving one pressure member, and means operable under the power of the machine for moving the other pressure member and for locking the clamping members upon the work.
30. In a machine for applying a heel-set to a shoe-assembly, the heel-set including members co-operating to embrace said shoe-assembly, in combination, a movable abutment adapted for contact with one of the members, and a lifting member co-operating with said abutment and contacting with the other of said members, the shoe-assembly being yieldably engaged between said members in response to the action of the lifting member upon the abutment.
35. In a heel-setting machine, the combination with a heel-set including a U-shaped member adapted to embrace a shoe-assembly, of a support having a channel to receive the bight of the U-shaped member and with a guideway extending from the channel, a slide movable in the guideway, and means for moving the slide to disengage from the support the bight of the U-shaped member.
40. Apparatus for mounting a heel upon a shoe, comprising, in combination, means for pressing the heel upon the shoe, and means co-operating with said pressing means and including a flexible bridging member adapted to yield upon engagement of its opposite ends with the tread and rear faces of the heel.
45. In a heel-setting machine, co-operating clamping members for a shoe-assembly, a member carried by one of the clamping members for contact with the tread and rear faces of a heel, and opposite abutment members for engagement with the clamping members.
50. In a heel-setting machine including, in combination, a body member for embracing a shoe-assembly, and a flexible member pivoted upon the body member for engagement with the tread and the back of the heel and adapted to bend for self-adjustment under applied pressure.
55. A heel-set including, in combination, a clamp comprising a first member for embracing a shoe-assembly, a second member shiftable upon the first member for engagement with the shoe-assembly, and means carried by said second member for engaging both the tread and the back of a heel.
60. A heel-set including, in combination, a clamp comprising a first member for embracing a shoe-assembly, a second member shiftable upon the first member for engagement with the shoe-assembly, and a member mounted upon the second clamp member to rock and move bodily thereon, the thus-mounted member being arranged for engagement with both the tread and the back of a heel.
65. A heel-set including, in combination, a clamp comprising a first member for embracing a shoe-assembly, a second member shiftable upon the first member for engagement with the shoe-assembly, and a flexible member mounted upon the second clamp member to rock and move bodily thereon, the thus-mounted member being arranged for engagement with both the tread and the back of a heel and adapted to bend between its points of engagement.
70. In a machine for applying to a shoe-assembly a heel-set provided with locking means, abutment means for engagement with the shoe-set, and means co-operating with the abutment means and movable under the power of the machine for actuating the locking means of the shoe-set.
75. In a machine for applying to a shoe-assembly a heel-set provided with locking means, opposite abutment members for engagement with the shoe-set, and means mounted upon one of the abutment members and movable thereon under the power of the machine for actuating the locking means of the shoe-set.
80. In a machine for applying to a shoe-assembly a heel-set provided with locking means, movable abutment means for engagement with the heel-set, means for actuating the locking means, a member for connection to a source of power, connections to the member for moving the abutment means, and connections to the member for actuating the locking means during a portion only of the abutment-moving cycle.
85. In a machine for applying to a shoe-assembly a heel-set provided with locking means, movable abutment means for engagement with the heel-set, means for actuating the locking means, a member for connection to a source of power, connections to the member for moving the abutment means into its engaging relation and then holding such engagement, and connections to the member for actuating the locking means during the time the engagement is held.
90. In a machine for applying to a shoe-assembly a heel-set provided with locking means, a support for the heel-set and shoe-assembly, a pressure-head movable toward and from the support, and lock-actuating means carried by the head.
95. In a machine for applying to a shoe-assembly a heel-set provided with locking means, a support for the heel-set and shoe-assembly, a pressure-head movable toward and from the support, a shaft rotatable in the head, a wrench for the locking means carried by the shaft, and gearing for transmitting power to the shaft.
100. In a machine for applying a heel-set to a shoe-assembly, opposite means for pressing the heel-set upon the shoe-assembly, lock-actuating

- means carried by the pressure means and co-operating with the heel-set to secure it upon the shoe-assembly, and power means for operating the pressure means and lock-actuating means.
24. In a machine for attaching a heel-set to a shoe-assembly, means including an abutment and a lifting member co-operating with said abutment to press the heel-set upon the shoe-assembly, lock-actuating means carried by the abutment and co-operating with the heel-set to secure it upon the shoe-assembly, and power means connected to the lifting means and lock-actuating means for operating said lock-actuating means while the lifting member is in pressing relation.
25. A heel-setting machine including, in combination, a pressure-head, a shaft rotatable in the head, a clutch member rotatable with and yieldably supported for movement axially of the shaft, and a wrench yieldably supported upon the shaft for frictional engagement with the clutch member.
26. The combination with a heel-set including a U-shaped body member, a transverse plate member shiftable on the legs of the body member and means including a rotatable locking member carried by the plate member for retaining it in engagement with the body member, of an abutment-head provided with spaced plate-engaging and leg-receiving portions, a rotatable wrench adapted to engage the locking member, a shaft rotatable in the abutment-head and axially movable therein in response to retraction of the wrench, and a clutch member rotatable by the shaft and yieldable thereon in engagement with the wrench.
27. The combination with a heel-set comprising a U-shaped member adapted to embrace a shoe-assembly, a plate member upon the legs of the member for engagement with the shoe-assembly and means including a rotatable wedge member carried by the plate for retaining it in engagement with the shoe-assembly, of a head adapted to receive the legs of the U-shaped member and to engage the plate, a lever, yieldable connections between the lever and head, a lifting member contacting with the U-shaped member, cam mechanism for operating the lifting member, means operating with said cam mechanism for rotating the wedge member, said means including an intermittently operating gear, a shaft journaled in the head, a socket member rotatable by the shaft for engagement with the wedge member and means for connecting the gear with the shaft, and means common to the cam mechanism and gear for operating them in definite time-relation for the actuation of the lifting member and socket member.
28. A machine for setting a heel upon a shoe including, in combination, a frame, a guideway in said frame, a head having a portion movable in the guideway, a pair of members supported on and extending on opposite sides of the guideway and provided with projections for opposite engagement with the head-portion, and means engaging the members for urging the projections against the head-portion.
29. In a machine for applying a heel-set to a shoe-assembly, upper and lower abutment members relatively movable to press the heel-set upon the shoe-assembly, the upper abutment having means by which the shoe-set may be suspended upon it.
30. In a machine for applying to a shoe-assembly a heel-set having a U-shaped member
- and a plate movable thereon, opposite pressure members, and means carried by one of the members for engaging the plate of the heel-set to cause the maximum separation between it and the bight of the U-shaped member.
31. In a machine for applying a heel-set to a shoe-assembly, upper and lower abutment members relatively movable to press the heel-set upon the shoe-assembly, and supporting members movable upon the upper abutment into and out of heel-set-engaging position.
32. In a machine for attaching a heel-set to a shoe-assembly, a heel-set including a transverse plate member and a member having spaced legs variably engaging the plate member, in combination, a member for supporting the heel-set in the machine for the reception of the shoe-assembly, and means movable upon the supporting member into and out of retaining engagement with the plate.
33. In a machine for applying a heel-set to a shoe-assembly, a movable pressure-head, fingers pivoted upon the head, and means for yieldably urging the fingers toward the head.
34. In a machine for applying to a shoe-assembly a heel-set having a U-shaped member and a plate member movable thereon, a movable pressure-head having a recess to receive the plate, and means carried by the head for retaining the heel-set in the tubular portions and in the recess.
35. In a machine for applying to a shoe-assembly a heel-set having a U-shaped member and a plate member movable thereon, a movable pressure-head having tubular portions to receive the legs of the U-shaped member and a recess to receive the plate, and slotted fingers pivoted upon the head for engagement with the plate.
36. In a machine for applying to a shoe-assembly a heel-set having a U-shaped member and a plate member movable thereon, a movable pressure-head having tubular portions to receive the legs of the U-shaped member and a recess to receive the plate, slotted fingers pivoted upon the head for engagement with the plate, a spring arranged to urge the fingers into plate-retaining relation, and a handle by which the fingers may be moved for the reception of the heel-set.
37. A heel-set including, in combination, a U-shaped member for embracing a shoe-assembly, the legs of the U extending upon opposite sides of the counter-portion of the shoe, and flap-pressing means pivoted upon the bight connecting the legs of the member.
38. A heel-set including, in combination, a U-shaped member for embracing a shoe-assembly, a shackle pivoted upon opposite extremities of the bight of the U-shaped member adjacent to the legs of the U, and a flap-pressing head movable upon the shackle.
39. A heel-set including, in combination, shoe- and heel-clamping members movable one upon another, a carrier member mounted upon the clamping members, and a flap-engaging member movable upon the carrier member.
40. A heel-set including, in combination, shoe- and heel-clamping members movable in co-operation with each other, a carrier member mounted upon the clamping members, a flap-engaging member movable upon the carrier member, and means for retaining the flap-engaging member in different adjusted positions upon the carrier member.
41. A heel-set including, in combination, a U-shaped member for embracing a shoe-assembly,

a shackle pivoted upon the U-shaped member, a screw threaded through the bight of the shackle, and a flap-pressing head carried by the screw.

42. A heel-set including, in combination, a U-shaped member for embracing a shoe-assembly, a shackle pivoted upon the U-shaped member, a screw threaded through the bight of the shackle, a flap-pressing head, and a universal joint connecting the screw and head.

10 43. In a heel-setting machine, co-operating

clamping members adapted for engagement of a shoe-assembly, a flexible member carried by one of said clamping members for yieldably engaging the shoe-assembly, operating means for causing contact of said flexible member with the shoe-assembly, means for locking said flexible member in contact with the shoe-assembly, and other operating means including a lifting member for engaging the other clamping member.

5 WALTER A. THUM. 10
